UNITED STATES PATENT OFFICE.

JOHN RINGEN, OF ST. LOUIS, MISSOURI.

SAD-IRON HEATER.

SPECIFICATION forming part of Letters Patent No. 336,591, dated February 23, 1886.

Application filed January 17, 1885. Serial No. 153,127. (Model.)

To all whom it may concern:

Be it known that I, JOHN RINGEN, a citizen of the United States, residing at St. Louis, in the county of St. Louis and State of Missouri, 5 have invented certain new and useful Improvements in Sad-Iron Heaters, of which the following is a specification, reference being had to the accompanying drawings.

My invention relates to devices for heating 10 sad-irons; and my object is to provide a rest or frame which will securely hold one or more sad-irons in such a manner that they may be readily and quickly heated both by conduction through the rest or frame and by the direct action 15 of the heated air or products of combustion rising from a gas-stove or other source of heat upon which the device may be placed, and striking directly against the bottoms of the irons.

20 My invention consists in a peculiar framework of pyramidal shape, cast in one piece, having a number of rests for the heels of the flat-irons, and inclined open sides, against which the bottoms of the irons rest, so that 25 they are exposed to the hot air, gases, &c., which rise from the stove into the interior of the frame-work.

The invention also consists in various details of construction, which will be fully hereinafter described.

30 Drawings accompany this specification, in which Figure 1 represents a perspective view of the device, with a sad-iron in position to be heated. Fig. 2 is also a perspective view, 35 looking directly at one of the inclined sides.

A represents a pyramidal frame cast in one piece, and composed, essentially, of a base, B, having a large central opening, and three or more inclined recessed standards, which form 40 inclined side faces, A', the number of which depend on the number of sad-irons to be held at the same time. I have shown the pyramidal frame in this instance as of triangular cross-section, so that there are three inclined 45 faces, A', meeting at a common apex, a. The standards are cast angular in cross-section, having a sharp external edge extending down to the point a', where they become nearly perpendicular, as shown at a', to the point where 50 they are connected to the base. It will readily be understood that these angular stand-

ards, diverging from the apex toward the base, 55 form the open side faces against which the sad-irons lean. The heel of the sad-iron rests upon the base B, which is composed of three recessed parts connected together by flat webs b', so that a broad stable support is formed. The top of the part B is formed at such an angle (slightly less than a right angle) to the inclined side face that it tends to tip the iron 60 slightly inward against the side face.

When the irons are in place, the frame becomes a closed chamber, into the interior of which the hot air and products of combustion 65 ascend in direct contact with the bottoms of the irons. The iron is heated to a certain extent in addition by conduction through the heated frame, the walls of which are exceedingly thin, as shown. In order to permit the products of combustion to escape, I may cast 70 with the frame small projecting lugs c, against which the upper part of the iron rests, so that a passage is formed for the escape of the heated air. I prefer, however, to make a groove, d, at the top of the opening in the side face, and 75 also in the face of each of the inclined standards, which answer the same purpose.

When the device is set upon a hot surface, or otherwise exposed to heat, the recessed parts of the base become hot-air chambers, and 80 each part is provided with an orifice, d', through which the hot air escapes in contact with the heel of the iron, which is also heated by conduction. As a matter of additional security, I may cast lugs c' upon the top of the 85 heel-rests, which prevent the iron from slipping off the rest. From the pyramidal shape and hexagon base formed by the heel-rests B and webs b' the device is very firm and stable, and even when one iron only is upon it the 90 center of gravity is brought so low that it cannot be overturned.

Having thus described my invention, what I claim as new, and desire to secure by Letters Patent, is—

1. A sad-iron rest composed of a pyramidal frame having open side faces, an open base to admit the products of combustion to the interior, and a recessed heel at the bottom of each side face, whereby the irons, when in place, 100 close the openings in the side faces, substantially as described.

2. A sad-iron rest composed of a pyramidal frame having inclined open side faces, an open base to admit the products of combustion to the interior, recessed heel-rests at the bottom 5 of the side faces and set at an angle thereto, and having apertures d' , and means for allowing the escape of the products of combustion from the interior of the frame, substantially as described.

3. A sad-iron rest composed of a pyramidal frame, A, having inclined open side faces, A',

recessed heel-rests having apertures d' , and inclined grooves d in the side faces, the entire frame being cast in one piece and adapted to be placed upon a stove or other heated surface, 15 substantially as described.

In testimony whereof I affix my signature in presence of two witnesses.

JOHN RINGEN.
